UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

REINFORCED STEP RAIL JOINT.

Application filed October 8, 1926. Serial No. 140,333.

This invention relates to compromise or step rail joints for connecting the abutting ends of dissimilar rails of different height or section so that the gage and surface there-
5 of are brought into and held in alinement.

Heretofore the general practice has been, in the making of compromise or step rail joints, to form the bars for such joints of steel or malleable iron castings of a design
10 and configuration corresponding to that of the rail sections to be united, besides providing for the stepped relation of the rail supporting base sections. That is a well known construction open to the objection of
15 placing a cast rail joint in track. Furthermore, it also has been the practice to make the bars for compromise or step rail joints by upsetting or distorting a rail joint bar or shape at its medial portion in order to obtain the necessary vertical and lateral offsets
20 to provide for the surface and gage side alinement of the rails.

In stepping down from the higher section to the lower section of the bar the practices
25 heretofore followed in the making of such bars inevitably weakens the same at its central or medial portion where the offsetting occurs. That is particularly true in the die press or hammer operations which are em-
30 ployed in making a step joint bar from a rolled rail joint shape, such operations neces-
sarily distorting the metal at the points of offset and producing a weakened structure at the very point where the full strength of the
35 strongest part of the bar should be main-
tained. Also, in some forms of step bars where reenforcement occurs at the center of the bar the same is usually in the form of flange or girder reenforcement extending
40 below the base of the high rail. Such reen-
forcement is objectionable because of inter-
ference with rail seating on the ties, requir-
ing at times either cutting off the flange or
45 girder reenforcement or gouging out the ties
to accommodate the same, the latter ex-
pedient being particularly objectionable and
destructive. Also, said type of girder re-
enforcement for step joint bars does not uni-
50 formly carry the reenforcement across the
joint at the meeting ends of the rails and
does not maintain the physical properties of
such reenforcement in proper relation to the
physical properties of both the high fishing
55 section and the low fishing section.

Accordingly, the present invention has in view the making of a compromise or step rail joint bar by a forging operation directly from an unshaped blank or billet of substantially the same area or bulk as the finished bar so that the bar will be shaped merely by the working of the metal, as occurs in rolling practice, without any distortion or bending strains being imposed on the bar at any point as it is being "worked" or developed into its finished shape with reenforced head, reenforced center and with a base reenforcement which does not extend below the base of the high fishing section.

A further object of the invention is to provide a compromise or step rail joint bar which shall be stronger throughout than the ordinary rolled shape which is distorted at the center to provide the stepping from one rail section to another, and which shall in fact have a better distribution of metal, with no distortion, than any compromise or step rail joint bar made according to previous practice. Also, the invention contemplates a forged compromise or step joint bar whose center or medial portion is stronger than its lower fishing section and may be as strong or stronger than its high fishing surface, the reference here made to strength meaning the physical properties, and particularly the moment of inertia.

With these and other objects in view which will be understood by those skilled in the art the invention consists in the novel construction, combination and relation of features hereinafter particularly pointed out, illus-
85 trated and claimed.

While the invention necessarily is susceptible of structural modification without departing from the spirit or scope of the invention, a practical form, for illustrative purposes, is shown in the accompanying drawings, in which:

Figure 1 is a perspective view of a forged step joint bar embodying the present invention.

Figure 2 is a side elevation of a compromise or step joint embodying the present invention; the view showing the rails in position.

Figures 3, 4, 5, 6, 7 and 8 are cross-sectional views of the joint respectively at different points throughout the medial portion thereof between the inside bolts of the joint;

the lines of section for these figures being respectively indicated by the section lines 3—3, 4—4, 5—5, 6—6, 7—7 and 8—8; all of these views looking in the same direction and in the center section of line 5—5 the high rail is indicated by dotted lines.

Similar references designate corresponding parts in the several figures of the drawings.

- 10 In carrying forward the invention no change is involved in the general character of the joint itself nor in the functions thereof, as the invention has special reference to the bar construction which admits of utilizing a forging operation to "work" the metal into the finished shape from a plain blank or billet.

To illustrate the important features of the invention reference is made in the first place 20 to Figure 2 of the drawings, which includes the rails R and R', respectively of different height and section, and which must be alined, and held alined, both as to surface and gage. Also, in this figure of the drawings the two 25 dissimilar rails are shown connected or spliced by the step joint bar, generally designated by the reference letter B and formed with the high and low fishing sections 1 and 2, which respectively engage and fit the fishing spaces of the high and low rails R and R'.

According to the present invention it is intended that each joint bar B shall be of the same general construction throughout, 35 that is, provided with the upright web portion 3, a reenforced head member 4 and the out-turned foot flange 5. The head member 4 of the bar preferably is provided with the outer reenforcing rib 6 throughout, and with 40 a wheel flange clearance 7 throughout, while the foot flange 5 engages and fits the upper side of the flange of the rail. A distinctive feature of the invention is the provision of a novel medial or central reenforcement for 45 the bar, preferably at the outer side thereof only. This medial or central reenforcement may assume different shapes, but preferably occupies a position between the inside bolt holes designated x, on Figures 1 and 2, and 50 not extending below the base of the high rail. To illustrate such reenforcement there is shown in Figures 2, 3 and 4, by dotted lines, the usual outside configuration of the unreenforced bar of the type selected for 55 illustration, and at the outer side of the web of the bar there is provided a reenforcing gusset of metal connecting with the head reenforcement 6, as indicated at 8, and a corresponding reenforcing gusset of metal 9 60 sweeping over the lower outer fillet of the joint bar, and this lower reenforcing gusset of metal 9 is preferably merged into an enlarged reenforcing flange 10 which is a continuation, at the center of the joint, of the 65 outer edge portion of the foot flange of the

bar and projects substantially below the base of the low rail R', but not below the base of the high rail R.

All of the described reenforcement is confined preferably between the two inside bolt holes x and between the section lines 4 to 7 inclusive provides a section whose moment of inertia and other physical properties are approximately the same, or more properly speaking, are approximately at least the same 75 as the corresponding properties of the high fishing section of the bar and are greater than the low fishing section of the bar.

Thus, the special reenforcement described in effect preferably carries the full strength 80 of the high fishing section of the bar to a substantial distance past the center of the joint at the meeting ends of the rails so that the medial part of the bar which crosses 85 the joint at its center is stronger than the low fishing section of the bar. An additional important advantage of a construction of this kind is that the high fishing section 1 of the bar may be combined with any number of lower fishing sections 2, according 90 to the type and section of low rail to be joined to the high rail, thus permitting of economy in the use of the die parts for making the high fishing section 1 of the bar and its reenforcing extension past the center of 95 the bar.

It also will be noted that a distinct advantage of the special reenforcement described is that it does not extend below the base of the high rail and therefore does not come 100 between the ties in the manner of that class of rail joints having a depending girder reenforcement between the ties and extending below the level of the tie upon which rests the high rail, thereby overcoming the 105 objections heretofore pointed out, to the use of the distorted and deflected girder reenforcement for compromise or step rail joints. Furthermore, distinctive features of the invention reside in the joint bar being shaped 110 throughout from the same body of metal and having an unequal distribution of such metal to provide the elements herein described, and in the feature of employing the special reenforcement claimed with a ribbed reenforced-head type of step rail joint bar. 115

From the foregoing it is thought that the construction and utility of the herein described invention will be now apparent without further description and it will be understood that changes in the form, proportion and minor details of construction may be resorted to, without departing from the spirit of the invention and scope of the appended claims.

I claim:—

1. A step rail joint bar of a one-piece forging formed with high and low fishing sections respectively, the said bar having an integral medial reenforcement confined be- 130

- tween the inside bolt holes of the bar and presenting an enlargement of metal solely at and upon the outer side of the bar.
2. A step rail joint bar of one-piece formation throughout and formed with high and low fishing sections respectively, said bar having a graduated enlargement of metal solely at and upon the outer side thereof between the inside bolt holes.
- 10 3. A step rail joint bar of a one-piece forging formed with high and low fishing sections respectively, said bar having a medial enlargement of metal at its outer side, the said enlargement of metal having a proportional distribution of metal to provide a substantial equivalence between its physical properties and the physical properties of the high fishing section.
- 20 4. A step rail joint bar of a one-piece forging formed with high and low fishing sections respectively, said bar having a medial enlargement of metal solely at its outer side, the said enlargement of metal having a proportional distribution of metal therein whereby it possesses greater strength than the strength of the low fishing section.
- 30 5. A step rail joint bar of a one-piece forging formed with high and low fishing sections respectively, said bar having a medial enlargement of metal at its outer side, the said enlargement of metal having a proportional distribution of metal therein whereby it possesses a strength approximately at least equal to the strength of its high fishing section and greater than the strength of its low fishing section.
- 40 6. A step rail joint bar of a one-piece forging formed with high and low fishing sections respectively, the said bar having a medial enlargement of metal crossing the vertical plane between the meeting ends of the rails and having a proportional distribution of metal therein to provide a moment of inertia greater than the corresponding property of the low fishing section.
- 50 7. A step rail joint bar of one-piece formation throughout and formed with high and low fishing sections respectively, said bar having a medial enlargement of metal solely at and upon the outer side thereof between the inside bolt holes, said enlargement of metal including the underside of the bar head, the upper side of the bar foot, and being disposed below the bar foot.
- 60 8. A step rail joint bar of one-piece formation throughout and formed with high and low fishing sections, respectively, said bar having a medial enlargement of metal solely at and upon the outer side thereof between the inside bolt holes, said enlargement of metal including the underside of the bar
- head and the upper side of the bar foot, and being disposed entirely above the bottom extreme of metal in the high fishing section of the bar.
- 65 9. A step rail joint bar of one-piece formation throughout and formed with high and low fishing sections respectively, said bar having a medial reenforced portion including reinforcing gussets of metal at the outside fillets of the bar.
- 70 10. A step rail joint bar of one-piece formation throughout and formed with high and low fishing sections respectively, said bar having a medial reenforced portion including reinforcing gussets at the outside fillets of the bar and an enlarged reinforcing flange extending below the outer edge of the foot flange of the low fishing section of the bar.
- 75 11. A step rail joint bar of one-piece formation throughout and formed with high and low fishing sections respectively, said bar having a medial reenforced portion including reinforcing gussets at the outer side of the bar and an enlarged reinforcing flange extending over and below the outer edge of the foot flange of the low fishing section of the bar.
- 80 12. A step rail joint bar shaped throughout from the same body of metal and having an unequal distribution of such metal to provide the bar with high and low fishing sections respectively and a medial reinforcement confined between the inside bolt holes of the bar and extending vertically from the top to the bottom thereof solely upon its outer side.
- 85 13. A reenforced-head type of step rail joint bar shaped from the same body of metal throughout and provided with a medial reinforcement projecting solely from the outerside of the bar and integrated with the head reinforcement.
- 90 14. A reenforced-head type of step rail joint bar shaped from the same body of metal throughout and provided with a medial reinforcement projecting solely from the outerside of the bar and immediately underlying the head reinforcement.
- 95 15. A step rail joint bar shaped throughout from the same body of metal and having an enlarged laterally widened head including an outer projecting reinforcing rib, said bar also having solely at its outer side a medial reinforcement confined between the inside bolt holes and immediately underlying the said reinforcing rib.
- In testimony whereof I hereunto affix my signature.

VICTOR C. ARMSTRONG.
